UNITED STATES PATENT OFFICE.

WILLIAM H. KELLER AND ALBERT SCHINKEZ, OF GRAND HAVEN, MICHIGAN,
ASSIGNORS TO WILLIAM H. KELLER, INC., OF GRAND HAVEN, MICHIGAN, A
CORPORATION OF MICHIGAN.

PNEUMATIC-TOOL CONSTRUCTION.

Application filed September 22, 1919. Serial No. 325,294.

To all whom it may concern:

Be it known that we, WILLIAM H. KELLER, a citizen of the United States, and ALBERT SCHINKEZ, a former subject of the Emperor 5 of Austria, both residing at Grand Haven, in the county of Ottawa, in the State of Michigan, have invented certain new and useful Improvements in Pneumatic-Tool Constructions, of which the following is a 10 specification.

The invention relates to pneumatic hammers and like tools, comprising a cylinder with a piston reciprocable therein, a handle, and valve means for controlling the piston; 15 and the object of the invention is to provide a tool of the character indicated wherein the body of the tool,—the cylinder, the handle and the parts comprising the valve means, are advantageously constructed and 20 arranged, the aim being to simplify the construction whereby to facilitate the operation of machining the various parts of the tool as well as to permit of the quick and easy 25 assembling of such parts, thus reducing the cost of manufacture to a minimum.

In the accompanying drawings wherein we have illustrated a preferred embodiment 30 of our invention, Figure 1 is a central longitudinal sectional view through a pneumatic hammer constructed in accordance with our invention. Fig. 2 is a fragmentary sectional view taken on line 2—2 of Fig. 1. Fig. 3 is a detached perspective view of one 35 of the parts of our improved hammer.

The tool comprises generally, a cylinder 1 having a piston 2 reciprocable therein into and out of operative engagement with a tool 3 mounted in the forward end of the cylinder. 4 designates a handle comprising a 40 rear or hand portion 5 and a forward disk portion 6, while 7 designates generally valve means adapted to be clamped between the rear end of the cylinder and the disk portion of the handle.

At its rear end the cylinder 1 is provided 45 with an enlarged portion 8 equal in diameter to that of the disk portion 6 of the handle. The handle is provided with a passageway 9 for pressure fluid, which is controlled 50 by means of a valve 10 of usual construction. The passageway 9 in the handle extends into the disk portion 6, its lower end being closed by means of a plug 11 entered in the lower periphery of the disk portion 6.

To accommodate such passageway in the 55 disk portion, the latter is enlarged rearwardly as shown at 12 (Fig. 2).

The valve means comprises a valve block 13 and a pair of end plates 14 and 15, the valve block having a central bore 16 forming a chamber for a valve member 17. The opposite ends of this chamber are closed by the end plates 14 and 15, and the forward plate 15 closes the rear end of the cylinder. Any suitable arrangement of ports and 60 passageways, as for example, that shown in our copending application Serial No. 331,948, filed October 20th, 1919, may be employed to effect a reciprocation of the valve member and hence of the piston 2. Accordingly, it 70 is deemed unnecessary to describe herein the course of pressure fluid through the tool in the operation thereof.

To provide an annular exhaust chamber 75 around the valve casing formed by the valve block 13 and end plates 14 and 15, I provide an annular member or clip 18 which is preferably arranged so that its outer periphery lies flush with the outer periphery of the enlarged rear end 8 of the cylinder and with 80 the periphery of the disk member 6 of the handle. To this end the end plates 14 and 15 are made of a diameter sufficiently less than that of the rear end of the cylinder and the disk member to accommodate the thickness 85 of the annular member, and the valve block is made of a still smaller diameter, said valve block being provided with a series of radial exhaust ducts 19 leading from the valve chamber to the annular exhaust 90 chamber. To permit of the escape of the exhausted air or pressure fluid from the exhaust chamber, the annular member is provided in one side with a suitable opening such as a slot 20.

To secure the parts of the tool, that is to say, the cylinder, handle and valve casing together, we provide, preferably, a pair of bolts 95 21 arranged substantially diametrically opposite each other and on opposite sides of the enlargement 12 of the handle. Said bolts are entered through openings 22 provided in the handle, thence through openings 23, 24 and 25 provided in the rear end plate 14, valve block 13 and forward end plate 15, respectively, and finally are screw-threaded into the rear end of the enlarged portion 8 of the cylinder as shown at 26.

Preferably, resilient washers 27 are employed to lock the bolts against working loose. The bolts 21 thus constitute simple and effective means for firmly clamping the parts together in operative association.

It will be seen that we have provided a tool made up of a small number of parts, of extreme simplicity, which are so constructed as to be capable of association in an advantageous and effective manner. The cost of assembling is thus reduced to a minimum, and the parts are of such character that they may be produced at a very low cost.

We claim as our invention:

- 15 1. In a pressure-fluid-actuated tool, the combination of a cylinder having its rear end made of relatively large diameter, a handle having a forward disk portion, a cylindrical valve casing adapted to be interposed between the rear end of the cylinder and said disk portion, the rear end of said cylinder, casing, and disk portion being of substantially the same diameter, and means passing through said disk portion, the valve casing, and into the rear end of the cylinder, for rigidly securing the handle to the rear end of the cylinder while clamping the valve casing between said disk portion and the cylinder.
- 20 2. In a pressure-fluid-actuated tool, the combination of a cylinder, a handle having a forward disk portion, a cylindrical valve casing adapted to be interposed between the rear end of the cylinder and said disk portion, said valve casing comprising an inner cylindrical member and an outer annular member, with means for spacing the outer member from the inner member to form an exhaust chamber, and means passing through said disk portion, the valve casing, and into the rear end of the cylinder, for rigidly securing the handle to the rear end of the cylinder while clamping the valve casing between said disk portion and the cylinder.
- 25 3. In a tool of the character described, the combination of a cylinder, a handle, a cylindrical member adapted to be entered between the handle and cylinder, means on opposite sides of said cylindrical member between it and the cylinder and handle respectively whereby to close the rear end of the cylinder and to abut the handle, said member and means being constructed to provide a valve chamber having a valve therein, and bolts entered through the handle, the cylindrical

member and into the cylinder to clamp the parts together in operative association, the rear end of the cylinder being enlarged to accommodate said bolts.

4. A pressure-fluid-actuated tool comprising, in combination, a cylinder, a handle terminating in a forward disk portion of a diameter substantially equal to that of the rear end of the cylinder, valve means including a hollow cylindrical block, a pair of end plates upon the opposite ends of said block and forming therewith a valve chamber, and a valve member in said chamber, and means passing through the handle and valve casing and into the cylinder to clamp them together, said cylinder being enlarged at its rear end to accommodate said means.

5. A pressure-fluid-actuated tool comprising, in combination, a cylinder having a piston operable therein, a handle mounted at the rear end of the cylinder and having a forward disk portion, and valve means secured between said disk portion and the handle and said cylinder including a cylindrical block having a central bore, end plates closing said bore to form a valve chamber, a valve member operable in said chamber, and an annular member surrounding the valve casing in spaced relation with reference to said block to form an annular exhaust chamber, said block being of smaller diameter than said end plates and the end plates being of smaller diameter than the rear end of said cylinder and said disk portion of the handle.

6. A pressure-fluid-actuated tool comprising, in combination, a cylinder enlarged at its rear end and having a piston operable therein, a handle secured at the rear end of the cylinder and having a disk portion of a diameter substantially equal to that of the rear end of the cylinder, and valve means including a valve block having a central valve chamber closed at its opposite ends, said block being of substantially less diameter than the cylinder, and an annular member forming with said block an annular exhaust chamber and mounted with reference to the cylinder and disk portion of the handle so that its periphery lies substantially flush therewith.

In testimony whereof we have hereunto set our hands.

WILLIAM H. KELLER.
ALBERT SCHINKEZ.
